ELECTRIC PENCIL

Ralph H. Goldman, Chicago, Ill., assignor of one-half to David G. Einstein, Chicago, Ill.

Application May 24, 1933, Serial No. 672,697

1 Claim. (Cl. 219—29)

This invention relates to certain novel improvements in electric pencils, and has for its principal object the provision of an improved construction of this character which will be highly efficient in use and economical in manufacture.

An object of this invention is to provide a novel electric pencil having a hot point or writing tip adapted for various uses such as, for example, burning designs in wood, applying gold leaf 10 lettering to leather goods, and the like.

Another object of the invention is to provide an electric pencil which may be used with either A. C. or D. C. current.

A further object of the invention is to provide an electric pencil comprising a hot point or writing tip and a tubular handle having a finger grip portion and including a heat-dissipating structure for preventing absorption by the handle of heat from the writing tip and resistance element 20 that heats the same.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a perspective view showing the device applied to a typical use;

Fig. 2 is a longitudinal sectional view of the device;

Fig. 3 is an end plan view on line 3—3 in Fig. 2, showing the writing tip;

Fig. 4 is a sectional view on line 4—4 in Fig. 2, 35 showing the cooling unit in the handle;

Fig. 5 is a sectional view on line 5—5 in Fig. 2;

Fig. 6 is an enlarged sectional view on line 6—6 in Fig. 2; and

Fig. 7 is a perspective detail view of the hot 40 point or writing tip.

The new device is in the form of a pencil or stylus, indicated generally at 10, and includes a nib or writing tip 11, a tubular handle structure, generally indicated at 12, and a heat-dissipating unit 14 arranged between the nib 11 and the handle 12; said unit 14 coupling the nib 11 and handle 12 into a unit and preventing the heat from the nib 11 and its resistance unit 18 from heating the finger grip 23—24.

The nib 11 may be made of any suitable metal such, for example, as nichrome, chromel, or silver alloys, and has a tubular barrel 16 that is preferably made of a nickel silver alloy. Embedded in the barrel 16 is an electrically non-conductive, 50 heat-resistant tubular casing 15, which may be

made from any suitable material, such, for example, as mica. Arranged in the mica casing 15 is an electrically non-conductive, heat-resistant or refractory core 17, which may be made of porcelain or the like, and upon which is wound a resistance unit 18 for heating the nib 11.

Attached to one end of the resistance unit 18, as at 19, is a conductor 20, and attached to the other end of the resistance unit 18 is a conductor 21; these conductors 20 and 21 being led 10 through a refractory tubular section 22 of the handle structure 12 for connection to an electrical outlet or current source. The section 22 may be made of suitable material such, for example, as bakelite. 15

Surrounding the lower portion of the bakelite handle section 22 is a cork finger or hand grip which includes a tubular section 23 and a ring 24 arranged at one end of the section 23.

The heat-dissipating unit 14 provides a coupling between the barrel 16 of the nib or writing tip 11 and the tubular section 22 of the handle. This heat-dissipating unit 14 includes, in addition to the other parts presently to be described, a brass or monel cup-shaped ring 25 that is 20 fitted onto the lower end of the tubular handle casing 22. Fitted into the lower end of the tubular casing 22 is a refractory coupling member 26. This coupling member 26 is preferably made of the mineral known as lava, and has at its 30 lower end a flange 27 in which are provided a series of radially arranged air circulating holes 34. Also provided in the flange 27 is a series of radially arranged holes 31.

The heat-dissipating unit 14 also includes a 35 second cup-shaped perforated brass or monel ring 28 that is similar to the ring 25 but spaced therefrom and inverted toward the ring 25. This ring 28 is attached to a tubular refractory coupling member 29 that is also preferably made of 40 the mineral lava. This coupling member 29 has a flange 30 which is spaced from the flange 27 and in which a series of radially arranged air-circulating holes 35 are provided. Formed in the flange 30 of the refractory coupling member 29 in 45 alignment with the holes 31 are holes 36 and metallic air-circulating tubular rivets 32 are inserted through the aligned holes 31 and 36. These tubular rivets 32 may be made of suitable material, such as, for example, Monel metal, and 50 they have flanged ends 33 which tie the coupling members 26 and 29 together.

The writing tip or nib 11 is provided with three different and radially arranged points 37, 38, 39 (Fig. 3) for forming or inscribing either fine, 55

medium, or relatively heavy lines respectively in or on the work.

When circuit is closed through the resistance unit 18 the nib or writing tip 11 and the points or nibs 31, 38, 39, become hot, whereupon the pencil may be grasped by the cork finger grip 23-24 and the device applied to any type of work for which it is suitable such, for example, as inscribing designs in wood or other material, doing gold leaf lettering on leather goods, etc.

When the pencil is in use the heat generated by the resistance unit 18 is prevented, by the heat-dissipating means 14, from being transmitted by conduction to the handle and its finger grip 23-24 so that the latter at all times remains cool and safe to handle. This is effected by air circulation and convection currents which are set up, when the device is in use and the nib 11 is not, causing air to circulate through the perforated metal rings 25 and 28, through the air chamber that exists between the flanges 27 and 30 of the coupling members 26 and 29, and through the metal tubes 36 and the holes 34 and 35.

While I have illustrated and described the preferred form of construction for carrying my invention into effect, this is capable of variation and modification, without departing from the

spirit of the invention. I, therefore, do not wish to be limited to the precise details of construction set forth, but desire to avail myself of such variations and modifications as come within the scope of the appended claim. 5

Having thus described my invention what I claim as new and desire to protect by Letters Patent is:

A device of the type described comprising a tubular metallic point, an electrical resistance unit positioned within said tubular metallic point, insulating material surrounding the electrical resistance unit and positioned between the latter and the inner wall of said metallic point, a grip member, a mineral lava connection between 15 the grip member and said metallic point, said mineral lava connection comprising two portions provided with perforations, tubular rivets passing through certain of the perforations in said portions for connecting the two together, a perforated metallic disc associated with each of said portions, said metallic discs being larger in diameter than the cross-sectional perimeter of said grip member, insulating material disposed upon said grip member, and wires extending through 20 said grip member and connected with said electrical resistance. 25
